Primary Examiner — Antoine Duval Davis(74) *Attorney, Agent, or Firm* — Michael J Porco; Gerald Hespos; Matthew T. Hespos**(57) CLAIM**

The ornamental design for an electronic power meter, as shown and described.

DESCRIPTION

FIG. 1 is a front, right perspective view of an electronic power meter showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines are for the purpose of illustrating portions of the electronic power meter and form no part of the claimed design.
